BABY INCUBATOR

Erwin F. Hoffman, Madison, Wis.

Application March 24, 1933. Serial No. 662,459

5 Claims. (Cl. 128—1)

This invention pertains to improvements in baby incubators, and has primarily for its object to provide an exceedingly simple and comparatively inexpensive structure of the most convenient design for the insertion and removal of the infant, and which is both highly efficient in operation and automatically controlled.

Incidental to the foregoing, a more specific object resides in the provision of an incubator having the above characteristics, which is provided with adjustable thermostatic control of an electric heating medium, together with means for ventilating the interior of the cabinet, and humidifying the air circulated therethrough.

A still further object resides in the provision of means operable from the exterior of the cabinet for regulating the angular position of the infant's body.

Another object resides in the provision of a cabinet open at one end, and provided with a removable partition that serves as a closure for the heating compartment formed at the opposite end of the cabinet, thus facilitating insertion and removal of the infant, and providing for projection of its head from the heating compartment.

A still further object resides in the provision of a slidable glass panel for the heating compartment, whereby the body of the infant may be readily viewed, and access may be had to the cabinet for regulating the heat control, as well as providing for ventilation of the cabinet.

With the above and other objects in view, which will appear as the description proceeds, the invention resides in the novel construction, combination, and arrangement of parts, substantially as hereinafter described and more particularly defined by the appended claims, it being understood that such changes in the precise embodiment of the herein disclosed invention may be made as come within the scope of the claims.

In the accompanying drawings is illustrated one complete example of the physical embodiment of the present invention constructed according to the best mode so far devised for the practical application of the principles thereof.

In the drawings:—

Figure 1 is a longitudinal section through an incubator constructed in accordance with one form of the present invention, the view being taken on the line 1—1 of Figure 2.

Figure 2 is a front elevation with parts broken away and in section to more clearly illustrate structural features.

Figure 3 is a bottom plan view, with parts broken away and in section, and

Figure 4 is a perspective view of a modified form of the invention.

Referring now more particularly to the accompanying drawings, in that form of the invention illustrated in Figures 1 to 3, inclusive, the numeral 1 designates generally a cabinet comprising the side walls 2, a rear wall 3, and a top wall 4, which covers the rear portion of the cabinet, as best shown in Figure 1, it being noted that the side walls 2 are projected upwardly adjacent their rear ends, thus materially increasing the depth of the cabinet at the rear, in order to provide for the installation and proper positioning of the heating medium with relation to the position of the infant's body when placed in the cabinet.

Secured to the inclined edges of the side walls 2 is a front panel 5, which is provided with a pair of transparent slides 6, that serve to render the interior of the rear portion of the cabinet visible, and also permit access thereto, as well as ventilation of the cabinet.

Hingedly connected to the interior of the side walls 2, adjacent the panel 5, is a pair of doors 7 provided with cutout portions 8 adjacent their abutting and lower edges, thus forming an opening through which the head of an infant may be projected while the body is positioned within the rear heating compartment 9, as indicated in dotted lines in Figure 1.

In the present preferred form of the invention, the support for the infant comprises a drawer 10 consisting of a frame 11, the side rails of which are notched to slide upon the ways 12 secured to the interior faces of the side walls 2. Positioned within the frame 10, and pivotally connected to the side rails by means of a transverse rod 13 is a tiltable table 14 comprising a top 15 secured to the spaced longitudinal sills 16, which in turn are mounted upon the rod 13. Cross members 17, connected to the lower edges of the side rails adjacent their ends, serve to limit the tilting action of the table 14, which is rotatably adjusted to the desired angle by means of a threaded rod 18 projecting through the front 19 of the drawer frame, and which is provided with a hand-wheel 20 for manipulation thereof. As best shown in Figure 1, the threaded rod 18 is engaged in a clevis 21, which is pivotally connected to a bracket 22 carried by the center sill 16. Obviously, as the rod 18 is rotated, the clevis 21 is run in or out, causing the table to rotate upon the transverse bar 13, thus shifting

105
110

the table to raise or lower the head of the infant.

Inasmuch as some clearance must be provided in the opening formed in the doors 7, the same are provided with hooks 24, from which a cloth 25, indicated in dotted lines, is supported to surround the infant's neck and retain the heat within the compartment 9.

For heating the compartment 9, various forms 10 of electric elements may be employed, such as incandescent bulbs 26, which are secured to the interior of the top 4, and connected with a thermostatic control 27 secured to the rear wall 3, it being understood that the thermostat may be ad-

justed to operate at predetermined temperatures. A conventional socket 28 secured to the outer face of the rear wall 3 is connected to the thermostat, and receives a conventional cord plug 29, through which current is supplied to the lights 26.

For convenience a thermometer 29 is supported upon the rear wall 3, and where it is desired to humidify the air circulated through the openings 30 formed in the rear wall 3, and through the front panel 5, when the glass slides are open, a humidifier 31, in which a wick or felt pad 32 is positioned, is supported upon the interior of one of the side walls 2.

From the foregoing explanation, considered in connection with the accompanying drawings, 30 it will be readily seen that an extremely simple and inexpensive incubator has been provided, which can be readily transported from place to place, and can be easily controlled to provide any desired condition within the heating compartment 25 9 containing the infant's body.

It will further be noted that insertion or removal of the infant is materially facilitated by means of the sliding drawer, and the swinging doors 7, inasmuch as the drawer, when extended, 40 allows the infant to be properly arranged and positioned thereon outside of the cabinet, which renders the operation most convenient, after which it is merely necessary to slide the drawer inwardly and close the door 7, leaving the body positioned within the heating chamber, with the head projected therefrom and positioned in the open end of the cabinet, where it may be fed, 45 or otherwise observed without moving or disturbing the body, or opening the cabinet. Fur-

thermore, without disturbing the infant, or opening the cabinet, the angle of its body may be varied as desired by manipulating the hand-wheel 20.

In some instances where it may be desired to 30 provide a more inexpensive structure, although not as convenient or desirable, the sliding drawer 10 may be eliminated, and a permanent bottom 33 may be provided for the cabinet, such as shown in the modification of the invention illustrated 35 in Figure 4. Such bottom may be either rigid or adjustable, and, outside of the question of convenience, produces the same ultimate results.

I claim:—

1. A baby incubator comprising a cabinet having an open and closed compartment, a movable partition between said compartments, and an adjustable bottom support extending through the said compartments. 90

2. A baby incubator comprising a cabinet having open and closed compartments, a movable partition between said compartments, thermostatically controlled heating means for said closed compartment, and a lower support extending through both of said compartments. 95

3. A baby incubator comprising a cabinet having an open and closed compartment, a movable partition between said compartments, a lower support extending through both of said compartments, thermostatically controlled heating means for said closed compartment, means for ventilating said closed compartment, and a humidifier positioned in said closed compartment. 105

4. A baby incubator comprising a cabinet having an open and closed compartment, a movable partition between said compartments, a lower support extending through both of said compartments, a thermostatically controlled heating means for said closed compartment, a slideable transparent panel for said closed compartment, 115 and a humidifier positioned in said closed compartment.

5. A baby incubator comprising a cabinet having an open and closed compartment, a movable partition between said compartments, a slideable lower support extending through both of said compartments, and thermostatically controlled heating means for said closed compartment. 120
